(57) **CLAIM**

The ornamental design for a 5 valve port large bore double flange manifold, as shown and described.

DESCRIPTION

FIG. 1 is an elevated, perspective view of a 5 valve port large bore double flange manifold, showing my new design;

FIG. 2 is a top view thereof;

FIG. 3 is a bottom view thereof;

FIG. 4 is a rear view thereof;

FIG. 5 is a front view thereof; and,

FIG. 6 is a right side view, the left side view is a mirror image thereof.

The broken lines shown in the all of the figures are for illustrative purposes only and form no part of the claimed design.
